UNITED STATES PATENT OFFICE.

ROBERT GEORGE YOUNG, OF BREAM, ENGLAND.

SIGNALING APPARATUS.

1,273,979.

Specification of Letters Patent. Patented July 30, 1918.

Application filed July 21, 1917. Serial No. 181,985.

To all whom it may concern:

Be it known that I, ROBERT GEORGE YOUNG, subject of the King of Great Britain and Ireland, residing at Knockly Cottage, Bream, in the county of Gloucester, England, have invented new and useful Improvements in Signaling Apparatus, of which the following is a specification.

This invention relates to signaling apparatus of the type used in mines and is of that class termed "non-cumulative", in which the signaling operation is effected by means of two ratchet wheels one driving the other through a unidirectional clutch, the retaining 10 detent of one ratchet wheel being controlled in operation by a timing device and a cautionary signal is exhibited when men are in the cage, and has for its object the improved construction and arrangement of 15 apparatus of this type whereby the present regulations of the Coal Mines Act 1911 of Great Britain are fully complied with, a single pointer only is necessary to indicate the particular signal given, a cautionary signal 20 is set when men are going to travel in the cage and remains visible until the end of the wind unless canceled by the signaller, the cancellation of any signal can only be effected in one of two ways while the cage 25 is in motion, either automatically during the operation of the winding gear when the cage is reaching or has nearly reached the end of its journey, or by signaling the last number on the dial, say 8, and lastly signal No. 1, 30 which according to the regulations is used to indicate "Stop" and "Start", is provided with the specific indication of either "Stop" 35 or "Start", the exhibition of which is controlled by the operation of the winding gear. 40 The invention consists in arranging mechanism as hereinafter described to carry out the above objects comprising a ratchet wheel upon an axis within a frame which wheel is spring or weight urged in one direction, 45 for example, counter clockwise. With this ratchet wheel engages a dog mounted upon a movable member connected to the onsetter's or banksman's communication cord or wire. A pivoted detent or equivalent means 50 is mounted on the frame in order to prevent the backward motion of the ratchet wheel when moved forward by the dog on the movable member. This dog is adapted to co-act with a tripping lever controlled by a 55 time device such as a dash pot. The ratchet wheel co-acts with a second ratchet wheel also spring or weight urged in one direction

through the medium of a unidirectional clutch, and is retained from backward movement by a pawl, the movement of which is controlled by a device in co-action with the engine movement or with the cage so as to become operative when the cage has reached a given position in the shaft. The first ratchet wheel will return to the zero position when its detent is released by the dashpot reaching its lower terminal position. When the first ratchet wheel is moved through the space of three teeth means are provided on said ratchet wheel to cause at 60 this point the exhibition of the cautionary signal "Men on cage" and said signal is kept in position by retaining means adapted to be released either by the engine movement or the cage movement when the latter has attained a given position in the shaft, or by means provided on the second ratchet wheel adapted to come into action when the ratchet wheel has been moved through the space of 8 teeth. This second ratchet wheel 65 carries the pointer which indicates on the dial the number of consecutive signaling steps made by the onsetter or banksman. Each ratchet wheel is conveniently provided with a drum around which a cord is wound 70 at the end of which is suspended a weight 75 to urge the ratchet wheel in an anticlockwise direction.

The device operated by the engine movement or by the cage reaching a given point 80 in its journey, is adapted to act upon a device pivoted about an axis in a state of unstable equilibrium, so arranged that when the engine movement has pulled the device past the point of unstable equilibrium 85 gravity will complete the movement and cause electrically or otherwise the release of the retaining pawl of the ratchet wheel of the second drum when the cage reaches a predetermined point so that the pointer returns to zero. 90

If the signals are given sufficiently rapidly the sluggish movement of the dash pot prevents the detent of the ratchet wheel of the first drum from coming out of action, or if 95 another signal is given while one is already on the indicator unattended to the ordinary cumulative effect from a series of pulls of the communication cord is rendered of a non-cumulative effect owing to the movable 100 member connected to the banksman's communication cord co-acting with the detent of the second ratchet wheel so as to lift it out of action at each stroke. 110

The qualifying order of "Stop" or "Start" to No. 1 signal is effected by a plate which bears the two words so that one or other can be exhibited in proximity to No. 1 through 5 an aperture in the dial. When a signal has been given, for example "to lower," directly the engine moves, a device operated thereby puts into action a mechanism which enables the signal say "Start" already exhibited to 10 be canceled and the signal "Stop" to be exhibited when one pull is given on the communication cord.

Means are also provided whereby any attempt to signal when the engine is in motion 15 causes the qualifying signal "Stop" to immediately appear and the pointer to move to No. 1 with a corresponding ring.

In order that the invention may be the better understood I will now proceed to describe 20 the same in relation to the accompanying drawings, reference being had to the letters and figures marked thereon. Like letters refer to like parts in the various figures, in which:—

25 Figure 1 is a front view of the device with parts in position after an order to "stop" has been executed.

Fig. 2 is a side elevation of the same.

Fig. 3 is a front view of the rear frame 30 plate with its associated parts.

Fig. 4 is a rear view of the front frame plate and part of the dial plate.

Fig. 5 is a rear view of the rear frame plate.

35 Fig. 6 is a front view of the front frame plate.

Fig. 7 is a rear view of the dial plate with the qualifying signal "Stop" in position as shown in Fig. 1 with the engine at rest.

40 Fig. 8 is a similar view but showing the detent for retaining the "Stop" signal in position tripped by the banksman's cord so that the signal "Start" appears.

Fig. 9 is a view of the same mechanism as 45 shown in Fig. 8 but pushed into the inner position by the movement of the engine.

Fig. 10 is a view of the same mechanism but with the signal "Stop" raised into the 50 exhibited position by the operation of signaling No. 8 by eight pulls of the banksman's cord or the action of the electromagnetic control at a predetermined position in the travel of the cage.

Fig. 11 is a front view of the device with 55 the signals "No. 3", "Caution men on cage" and "Start" given together with the arrangement operated by the engine for controlling the "Stop" signal.

Fig. 12 is a view of the depth indicator 60 fitted with an electric switch arrangement with action depending on unstable equilibrium of a moving mass.

To carry the invention into effect I form 65 a framework consisting of a front plate a and a back plate a' connected together by

distance pieces a^2 and on the front plate a , a dial a^3 is mounted. In the back plate a' is rigidly held an axle b upon which is loosely mounted a ratchet wheel b' to which is attached a drum b^2 carrying a cord b^3 at the 70 end of which is attached a weight b^4 . Upon a fixed pivot b^5 is mounted a detent b^6 which engages with the teeth of the ratchet wheel b' . Adjacent to the ratchet wheel b' is a sliding bar c to which the banksman's or 75 onsetter's cord c' is attached. The bar c is adapted to slide in guides c^2 and pivotally carries a pivoted dog c^3 so arranged as to co-act with the teeth of the ratchet wheel b' . The bar c also carries a rod c^4 projecting 80 rearwardly through a slot in the plate a' and enters the slot c^5 in the flattened portion c^6 of the piston rod d^4 so as to raise the piston in the dashpot d^5 at each operation of the bar c by the onsetter or banksman. The 85 detent b^6 has a tail lever b^7 which rests upon the bent end d of a lever d' pivotally mounted on the rear side of the back plate a' . The opposite end d^2 of this lever is disposed within a slotted bridle d^3 connected to the piston rod d^4 and a timing device or dash pot d^5 . On the axle b is also mounted a second ratchet wheel e which also has a drum e' , cord e^2 and weight e^3 . The ratchet wheel e is operated by a unidirectional clutch disposed between the two drums consisting of a pin e^4 on the drum b^2 which enters an annular groove e^5 in the drum e' . The annular groove e^5 does not extend the whole distance around a small solid portion e^6 being 90 left to form a driving abutment. A detent f is mounted on a fixed pivot f' supported in the front plate a and has a short tail piece f^2 . At the upper end of the detent f is a pin f^3 which projects through the circular slot f^4 in the front plate a . The drum e' carries a sleeve e^7 at the outer end of which is fastened the pointer e^8 which registers with the various signals 0 to 8 as indicated in Figs. 1 and 11. The zero position of the ratchet wheel b' is determined by a pin b^8 carried thereby which contacts with a fixed abutment b^9 mounted on the back plate a' . The ratchet wheel b' also carries a pin b^{10} which is located at such a 100 position that when the bar c has been operated three times it contacts with the right angles lever g slidably mounted on a pin g' mounted on the front of the back plate a' . The ratchet wheel b' also carries a 105 shrouding b^{11} so that when 8 strokes have been carried out by the bar c the shrouding b^{11} prevents the dog c^3 from engaging the teeth of the ratchet wheel b' .

On the rear side of the plate a is mounted 110 a plate a^4 on which the cautionary signal "Men on cage" is indicated and this signal is shut off from view by a curtain plate a^5 carried at the upper end of a bar a^6 slidably mounted on the rear side of the front plate 115

a. This bar is retained in the upper position by a detent h carried by an axle h' pivotally mounted in the plates a and a' and having a lever h^2 the end of which co-acts with a 5 bar h^3 slidingly mounted on a pivot h^4 . The bar h^3 has a projecting tooth h^5 extending laterally so as to come into the path of the bent end d of the lever d' when the bar h^3 has been moved into the said path by the 10 pin b^{10} contacting with the right angled lever g . The slotted arrangement on the right angled lever g is for the purpose of allowing this lever to recede from the ratchet wheel b' when the pin b^{10} passes it 15 on the return stroke, the movement of the lever g in the opposite direction being restricted by a stop g^2 .

The signal 1 on the dial has an aperture i behind which is mounted a vertically sliding plate i' on the front of which are inscribed the words "Stop" and "Start" in such a position that either word can be exhibited through the aperture i at any one time.

25 The plate i' is operated by a pair of bars i^2 and i^3 connected together by links i^4 to form a parallel motion, the bar i^2 resting against a flange i^5 carried by the plate i' . One of the links i^4 has a projection i^6 with which 30 a weighted detent i^7 pivoted on the bar i^3 engages. The bars i^2 and i^3 are mounted on the rear of the dial a^3 so as to slide a certain distance in a lateral direction, and this sliding movement is effected by the bar i^3 being 35 connected to a bell crank lever k , an arm of which engages with a weight k' slidingly mounted upon an axle k^2 and revolved by an angular toothed clutch k^3 driven by bevel gearing k^4 through a wheel k^5 operated by 40 the engine or associated gearing.

The detent i^7 is tripped out of engagement with the link i^4 when in the position shown in Fig. 7 by means of a sliding piece i^8 mounted on the back of the dial a^3 which is 45 operated by a lever i^9 by means of a bar i^{10} carried by and projecting from the sliding bar e .

When the bars i^2 and i^3 are in their innermost position as shown in Fig. 9, the right 50 hand end of the bar i^2 is so disposed as to be immediately over the pin f^3 .

On the sliding bar e is mounted a laterally extending arm i^{11} which engages with the under side of the detent f and on raising 55 same the pin f^3 engages the under side of the bar i^2 and raises it so that the detent i^7 maintains it in the upper position as indicated in Fig. 10. When the engine is stationary the parts of this device are as indicated in Fig. 7.

On the ratchet wheel e is mounted a pin e^9 which is located on the eighth tooth from the zero position of the wheel e in relation to the normal location of the hooked end 65 e^{10} formed at the end of a bar e^{11} which lat-

ter is slidingly mounted on the rear side of the plate a and pivotally connected to a lever e^{12} the end of which is also connected to the bar a^6 carrying the curtain a^5 . When the signal 8 is given by the onsetter or banksman 70 the pin e^9 comes in contact with the hooked end e^{10} and raises the bar e^{11} , lever e^{12} , bar a^6 and with it the curtain a^5 so as to cancel the cautionary signal "Men on cage".

In order to effect the cancellation of a signal when the cage has arrived at any predetermined position, viz., just before the end of the wind, I arrange on the depth indicator l a pivoted device l' which may conveniently be in the form of a tube containing mercury. This device has two fingers l^2 l^3 adapted to coact with a pin l^3 carried by the pointer l^4 of the depth indicator. The tube l' carries two contact producers l^5 which during the pivotal movement of the tube l' wipe electrical contacts l^6 in order to close an electric circuit. It will be seen that when the pointer l^4 in contacting with one of the fingers l^2 has tilted the tube l' past the horizontal the mercury running from one 90 end to the other end of the tube will overbalance the same and the tube l' will take up the position shown in full lines on the left hand side which represents the electrical switch for the opposite end of the wind 95 to that indicated in dotted lines on the right hand side. This electrical switch is adapted to control the electromagnet m shown in Fig. 4, the armature m' of which operates a lever m^2 connected by a bar m^3 pivoted to another 100 lever m^4 loosely mounted upon the pivot f' and adapted to contact with the tail end f^2 of the detent f . The tail end of the lever m^4 has a pin m^5 which engages in a slot m^6 in the bar m^7 pivoted to the lever e^{12} so that 105 when the signal "Men on cage" is exhibited and the cage arrives at a predetermined point in its travel, the electromagnet acts on the armature m' , lever m^4 in such a way that the pin m^5 contacting with the bottom 110 of the slot m^6 causes the curtain a^5 to be raised to cancel the signal "Men on cage".

The operation of the device is as follows:—When the banksman or opsetter pulls his cord c' any number of times sufficiently rapidly the dog c^3 picks up one tooth of the ratchet wheel b' at each stroke, and the ratchet wheel is retained in position by the detent b^6 , at the same time the piston of the dashpot d^5 is raised. If however too much time is allowed to elapse between the pulls on the cord c' the dashpot d^5 comes into operation by the piston dropping and the bridle d^3 carried thereby in dropping raises the bent end d of the lever d' and 120 withdraws the detent b^6 out of co-action with the ratchet wheel which latter consequently returns to zero. If eight pulls are given on the cord c' the shrouding b^{11} contacts with the dog c^3 and prevents any further 125

ther engagement with the ratchet wheel until the ratchet wheel has been returned to zero. When three pulls have been given on the cord c' the pin e^4 on the drum b^2 carries the drum e' , ratchet wheel e and pointer e^8 to signal No. 3 and each ratchet wheel is maintained in that position by the respective detents b^6 and f . As the third stroke is being finished the pin b^{10} contacts with the lever g which in turn moves the bar h^3 laterally so that the toothed projection h^5 comes into the path of the bent end d of the lever d' and as the dash pot d^5 comes into operation it not only trips the detent b^6 and allows the ratchet wheel b' to return to zero but in addition it raises the bar h^3 which in turn operates the lever h^2 , axle h' and detent h permitting the bar a^6 to drop and with it the curtain a^5 thus exhibiting the cautionary signal "Men on cage". Assuming now the cage is to be lowered the banksman pulls the cord c' twice. The first stroke releases the detent f from the ratchet wheel e so that the latter returns toward zero and at the same time the detent i^7 is tripped allowing the qualifying signal "Start" to appear at No. 1. As the engine begins to move the effort to drive the weight h' causes it to be raised by the action of the angular toothed clutch h^3 so that the bar i^3 is forced inward ready for co-action with the pin f^3 on the next signal being given. Just before the end of the wind the pointer l^4 tilts the tube l' and completes the electric circuit so that the electro-magnet m raises the detent f and cancels the signal. It will thus be seen that a signal can either be canceled automatically by the engine or the cage in its travel or by pulling eight times on the cord so that the dash pot when it comes into action allows the mechanism to return to zero. The second stroke picks up the ratchet wheel e and carries it around to signal No. 2.

In conclusion it may be pointed out that the following features are obtained by this invention:—

- (1) The signals are non-cumulative.
- (2) When a signal is given it can only be canceled while the cage is in motion by
  - (a) The winding gear when the cage reaches a predetermined position; or
  - (b) Signaling the designed canceling number, which remains in view until the next signal is given.
  - (3) A signal when once given is in evidence until canceled.
  - (4) The signal 1 is emphasized as to whether it means "stop" or "start".

Copies of this patent may be obtained for five cents each, by addressing the "Commissioner of Patents, Washington, D. C."

(5) Should the signal 1 be given when the engine is standing the signal 1 "To start" is shown but should the engine be in motion the action of signaling shows the qualifying signal "Stop".

I claim:—

1. A signaling apparatus winding engine and the like comprising in combination, a dial bearing signaling designations, a movable member to which a signaling cord or equivalent is attached, a dog pivoted on said member, a ratchet wheel urged in one direction adapted to be driven by said dog, a retaining detent on a fixed pivot co-acting with said ratchet wheel, a timing device reinforced at each movement of the movable member adapted to release the detent from the said ratchet wheel, a second ratchet wheel co-axially mounted with and adapted to be unidirectionally driven by the first ratchet wheel, a signaling pointer carried by said second ratchet wheel and located in relation to said dial, a retaining detent for said second ratchet wheel, means carried by said movable member for releasing said detent at each stroke, a cautionary signal independent of said dial signals normally not exhibited adapted to be put into normal position by said second ratchet wheel when a predetermined signal, say 8, is given, automatic retaining means for same and releasing means for said signal adapted to be operated by the said first ratchet wheel when another predetermined signal, say 3, is given, substantially as described.

2. A signaling apparatus as claimed in claim 1 in combination with a motor, a device operable by said motor, said device being capable of occupying two positions indicating "Stop" and "Start" respectively, and means operatively connecting the movable member to said device whereby the latter will occupy one position or the other according as said motor is active or inactive.

3. An apparatus as claimed in claim 1 in combination with a control device operated by the engine or cage at a predetermined point in its travel adapted to cancel the order just before the completion thereof, substantially as described.

In testimony whereof I have signed my name to this specification in the presence of two subscribing witnesses.

ROBERT GEORGE YOUNG.
